UNITED STATES PATENT OFFICE.

JOSEF MECERA, OF WASHINGTON, DISTRICT OF COLUMBIA.

PLAYING DEVICE FOR ZITHERS AND THE LIKE.

1,097,106.

Specification of Letters Patent.

Patented May 19, 1914.

Application filed August 2, 1913. Serial No. 782,642.

To all whom it may concern:

Be it known that I, JOSEF MECERA, a subject of the Emperor of Austria-Hungary, residing at Washington, in the District of Columbia, have invented certain new and useful Improvements in Playing Devices for Zithers and the like; and I do declare the following to be a full, clear, and exact description of the invention, such as will enable others skilled in the art to which it appertains to make and use the same.

This invention relates to improvements in key operated playing devices for zithers and like stringed musical instruments.

One object of the invention is to provide a device of this character having an improved construction and arrangement of keys by means of which the string engaging hammers are actuated.

Another object is to provide a playing device of the character described which may be readily applied to the musical instrument and when not in use is inclosed in a casing and may be readily carried by a suitable handle in a manner similar to that in which a suit case is carried.

With these and other objects in view, the invention consists of certain novel features of construction, combination and arrangement of parts as will be more fully described and claimed.

In the accompanying drawings: Figure 1 is a perspective view of my improved playing device inclosed in a casing and in condition for being carried; Fig. 2 is a perspective view showing the device applied to a zither for playing the same; Fig. 3 is a vertical cross sectional view of the device and a portion of a zither illustrating in full and dotted lines the manner in which the string engaging hammers of the device are actuated by the keys; Fig. 4 is a plan view of the device and a portion of the zither with the top of the casing of the device removed; Fig. 5 is a vertical cross sectional view similar to Fig. 3 illustrating the manner in which the device is inclosed in its casing; Fig. 6 is a vertical longitudinal section through the rear portion of the device and the rear ends of the keys taken on the line 6—6 of Fig. 4 and illustrating the damper or tone-controlling mechanism of the device; Fig. 7 is a detail perspective view of one of the keys showing more particularly the manner in which the hammers are arranged therein; Fig. 8 is a side view of one of the hammers.

Fig. 9 is a detail view of one of the stop engaging blocks in the inner ends of the keys showing the extension thereon which carries the damper pads. Fig. 10 is a detail sectional view taken on the line 10—10 of Fig. 3.

My improved playing device comprises a casing 1 consisting of side members 2 in which are secured the ends of a key supporting rod or shaft 3 on which are pivoted the keys 4 of the device. The end members 2 of the casing are connected at their rear ends by a rear side member 5 which forms the back of the casing and at the lower portion of their front ends, said end members are connected by a narrow front piece 6. The end members are further connected at their lower edges by a front lower section 7 which extends back about one-half the width 75 of the casing and between which and the rear side member 5 is an opening through which the hammers of the device engage the strings of the zither when the device is placed thereon. When not in use this space 80 in the bottom of the casing is covered by a removable bottom section 8 on the inner edge of which are arranged dowel pins 9 adapted to engage sockets in the edge of the section 7 while the outer edge of the section 85 8 is held in position by hooks 10 which are engaged with keepers secured in the rear side piece 5 as is clearly shown in Fig. 5 90 of the drawings. The end members 6 of the casing are rabbeted on their inner sides adjacent to their edges to receive the ends of the front and rear side and bottom sections of the casing and with the upper rabbeted edges of the end members is engaged a top or cover member comprising a rear stationary section 11 which is suitably secured in place and has connected to the lower side of its forward edge a brace bar 12 the ends of which are set into recesses 13 formed on the inner sides of the end members of the 100 casing as shown. Hinged to the forward edge of the stationary section 11 of the cover is a front section 14 which is adapted to be swung back onto the stationary section when the casing is open for playing and which is 105 swung over the upper front portion of the casing when the latter is closed. The section 14 has secured to its forward edge a front end closing strip 15 which when the section 14 is closed is brought down over the open 110 front upper portion of the casing and into engagement with the upper edge of the

2
lower front piece 6 as shown in Fig. 5 of the drawings.

Secured to the ends of the casing are laterally projecting attaching blocks or flanges 16 having therein vertically disposed screw holes 17 with which are adapted to be engaged thumb screws 18 which are designed to be screwed down into the frame of the zither when the playing device is applied thereto as clearly shown in Fig. 2 of the drawings.

Secured to the front piece 6 of the casing and to the strip 15 on the hinged section of the cover are members of a clasp 19 by means of which the cover is securely fastened in closed position. Also secured to the front piece 6 of the casing is a handle 20 by means of which the device may be readily carried when the casing is closed.

Secured in the casing at a suitable distance below the forward ends of the keys 4 is a stop bar 21 which is designed to limit the downward movement of the keys when struck in playing and on the upper edge of which is arranged a sound deadening strip 22 against which the keys strike and which deadens the sound or noise which would occur if the keys came down into engagement with the naked bar. Across the rear end of the casing below the rear ends of the keys is also arranged a stop bar 23 the ends of which are secured in the ends of the casing and with which the rear ends of the keys are engaged when the latter are in a normal position. On the upper edge of the stop bar 23 is arranged a sound deadening strip 24 of felt or other suitable material which prevents any sound from being made when the rear ends of the keys come into engagement with the bar 23.

The keys of my improved playing device are arranged similar to the keys of a piano or organ and the white keys are notched on their edges to form spaces for the black keys as shown. The rear portions of each of the keys have formed therein a longitudinal slot 25 and set into the rear ends of said slots are stop engaging blocks 26 which engage the stop bar 23 when the keys are in a normal position. On the blocks 26 are formed right-angularly downwardly projecting extensions or lugs 27 which project a suitable distance below the rear ends of the keys and on the lower ends of a certain number of the extensions 27 are secured felt pads 28 which are designed to engage the strings of the instrument and which thus form a damper mechanism controlled in a manner hereinafter described.

Immediately below the pivotal point of the keys 4 is a strip 29 on which at intervals are upwardly projecting spacing lugs 30 which project upwardly through the forward ends of the slots in certain of the keys and which are provided to prevent any lat-

eral movement of the keys on the rod 3 thereby preventing the keys from becoming wedged or crowding together to such an extent as would interfere with the free operation thereof.

Pivoted near their rear ends in the slots 25 of the keys 4 are string engaging hammers 31 each of which comprises a bar having on its forward end a downwardly extending offset head 32 to the lower edge of which is secured a strip 33 of felt or other suitable cushioning material. The opposite ends of the hammers 31 have also formed offset depending enlargements 34 to the rear edges of which are secured weights 35 whereby this end of the hammer is swung downwardly and the head end upwardly and which normally holds the hammers in this position.

Arranged transversely through the upper portion of the casing above the keys 4 and a short distance in advance of the pivotal connection of the hammers with the keys is a bar 36 forming a fulcrum for the hammers and the ends of which are set into and securely fastened in notches 37 in the inner sides of the end members of the casing. On the lower edge of the bar 36 is secured a sound deadening strip 38 of felt or other suitable material against which the upper edges of the inner portion of the keys strike when the outer ends of the keys are depressed in playing. When the inner portions of the keys are swung upwardly by the depression of the outer portion thereof the upper edges of the forward ends of the hammers 31 are brought into more or less forcible engagement with the bar 36 or rather with the sound deadening strip 38 thereon which serves as a fulcrum for said hammers. This engagement of the hammers with said strip or bar throws the forward ends of the hammers downwardly through the slots 25 in the keys 4 on the depression of the front ends of the keys and the weighted rear ends of the hammers move upwardly through the rear ends of the slots 25 as is clearly shown in full and dotted lines in Fig. 3 of the drawings. In this operation of the hammers the cushioned or padded heads 32 thereof are brought into engagement with the strings of the instrument thus sounding the latter. By providing the rear ends of the hammers with the weights 35 it will be seen that when the heads of the hammers strike the keys, the weighted opposite ends of the hammers will cause the heads thereof to instantly rebound and disengage the strings to a slight extent, and when the keys are released said weighted ends of the hammers will swing the latter all the way up to their normal positions. Arranged on the inner surface of the stationary section 11 of the cover is a sound deadening strip 39 against which the for-

ward ends of the hammers strike when the keys are released and said ends of the hammers swing upwardly by the weighted rear ends in the manner described and as is 5 clearly shown in Fig. 3 of the drawings.

Arranged between the stop bar 23 and the rear side of the casing and pivoted at one end to said stop bar is a damper regulating bar 40 which for a certain distance from 10 its pivoted end is reduced and which from said reduced portion to the opposite side of the casing engages the lower edges of the rear ends of the stop engaging blocks 26 of the keys and by means of which the keys 15 engaged with the bar 40 may be raised to a greater or less extent thus lifting and disengaging the damper pads 28 on the extensions 27 of the blocks 26 from the strings of the instrument. The free end of the bar 40 20 is reduced and extended through a slot 41 in this end of the casing. The reduced end of the bar 40 projects beyond the end of the casing and is secured to the rear end of a bar operating lever 42 which is fulcrumed as 25 at 43 to the outer side of the casing and to the forward end of said lever is connected the upper end of an operating rod 44 which extends downwardly and is connected with a suitable pedal or foot piece 45 one end 30 of which is intended to rest on the floor and the opposite ends to be supported above the floor so that the operator by placing his foot on the treadle may rock the lever 42 and thus lift its rear end and the damper-regulating bar 40 which controls the dampers on 35 the keys.

Having thus particularly described the nature of my invention what I claim is:

1. A playing device for stringed musical instruments comprising a casing adapted to be placed in position on and secured to the instrument when the device is in use and to be closed to permit the device to be readily carried when not in use, a series of keys 40 pivotally mounted in said casing, a series of hammers carried by and pivotally mounted in said keys, and a bar arranged in the casing in position to be engaged by the hammers when the keys are depressed and to 45 cause the hammer heads to move into engagement with the strings of the instrument.

2. A playing device for stringed musical instruments comprising a casing having an opening in its bottom and adapted to be 50 placed in position over the strings of an instrument to be played, a series of keys pivot- 55 ed in said casing, stop bars arranged beneath the front and rear ends of the keys, a series of string engaging hammers pivoted 60 in said keys, said hammers having on one end string engaging heads and on their opposite ends weights, a bar arranged in the

casing and adapted to engage said hammers and cause them to move into engagement with the strings of the instrument when the 65 keys are depressed, said hammers being instantly disengaged from the strings by the weights thereon and means to regulate the sound produced by the engagement of the hammer heads with the strings. 70

3. A playing device for stringed musical instruments comprising a casing adapted to be placed in position on the instrument to be played, a series of keys pivoted in the casing and having in their rear ends vertically disposed slots, string engaging hammers pivoted in the slotted ends of said keys and having on one end cushioned string engaging heads, retracting weights carried by the opposite ends of the hammers, stop bars 80 arranged in the casing below the front and rear ends of the keys, stop engaging blocks carried by the keys and having depending extensions, damping pads carried by said extensions and adapted to engage the strings 85 of the instrument, a bar arranged in the casing and adapted to be engaged by said hammers when the keys are depressed and to cause the hammer heads to move downwardly into engagement with the strings of 90 the instrument.

4. A playing device for stringed musical instruments comprising a casing adapted to be placed in position on the instrument and having a vertical slot in one end wall thereof, a series of keys pivotally mounted in the casing, string engaging hammers pivotally mounted in said keys, stop bars arranged in the casing below the ends of the keys, stop engaging blocks carried 95 by the rear ends of the keys and having depending extensions, damping pads arranged on said extensions, means to cause said hammer heads to move downwardly into engagement with the strings of the 100 instrument when the keys are depressed, a damper regulating bar arranged below the rear ends of the keys and having one end pivoted in the casing and the opposite end projecting through the vertical slot in said 105 casing, a bar operating lever pivoted to the casing and having one end engaged with the projecting end of said bar, and a foot treadle connected with the opposite end of said lever whereby the latter may be rocked to actuate 110 said damper regulating bar.

In testimony whereof I have hereunto set my hand in presence of two subscribing witnesses.

JOSEF MECERA.
